UNITED STATES PATENT OFFICE.

JOSEPH FREDERICK FRADLEY, OF NEW YORK, N. Y.

OPERA-GLASS.

SPECIFICATION forming part of Letters Patent No. 351,317, dated October 19, 1886.

Application filed August 11, 1886. Serial No. 210,614. (No model.)

To all whom it may concern:

Be it known I, JOSEPH FREDERICK FRADLEY, a citizen of the United States, residing at New York, in the county of New York and State of New York, have invented a certain new and useful Improvement in Opera-Glasses; and I do hereby declare the following to be a full, clear, and exact description of the invention, such as will enable others skilled in the art to 5
10 which it appertains to make and use the same, in connection with the accompanying drawings, in which—

Figure 1 is a perspective view of an opera-glass constructed in accordance with my improvement. Fig. 2 is a partial sectional view 15 through one of the barrels or body portions of the frame.

My improvement consists in forming the barrels or body portions of the frame of single thick tubular or hollow cylindrical portions of metal, which I prefer to ornament by hand-chasing.

Referring to the drawings, forming a part of this specification, A indicates the frame, which 20 is of the usual and ordinary construction, consisting of tubes connected to each other by cross-bars or tie-pieces, and in the upper ends of which the top lenses are mounted, as usual. I prefer to construct these tubes of hard rubber or vulcanite, and the tie-bars of metal, although I do not confine myself to the use of such material. The lower or larger lenses are also mounted in two annular pieces of hard rubber or analogous material, and these two 25 annular parts are connected to each other by a metallic cross-bar. The tubes carrying the top lenses are adjustable, to change the focus, by means of a thumb-nut or wheel mounted on a vertical rod, which is attached rigidly to the 30 top cross-bar and moves freely through the intermediate one, as usual.

B B represent the barrels or body of the frame, and they consist of a single thickness of metal, preferably the precious metals—as 35 gold and silver. I construct these barrels by cutting them of proper form, bending them

into tubular form, soldering them at their edges, and afterward completing them by spinning on a lathe; or I draw them up from tubes into the form required. The single thick metal 50 tubes thus formed constitute the barrels or body of the opera-glass. These metallic tubular parts are then hand-chased, to roughen them to prevent the glass from slipping in or dropping from the hand when in use. 55

Heretofore opera-glasses have been constructed with the barrels of hard rubber or analogous material, and they have also been covered with leather or velvet plush. When constructed of hard rubber, if the glasses should 60 happen to fall, the barrels or cases are frequently broken, and the leather and velvet become rapidly worn and defaced, so that the glass soon presents an unsightly appearance. Glasses of this character, on account of the 65 spiration of the hands of the user or the smoothness of the barrels, and of gloves, when worn, are not only soiled, but are easily dropped and frequently broken or injured. All of these difficulties are obviated by my improvement, 70 and, in addition, I am enabled to construct a most attractive and beautiful article of manufacture, as the gold or silver, oxidized or not, forms a striking contrast with the black rubber portion, and the facility with which these 75 metals can be ornamented by chasing renders the glass a most attractive and desirable one.

Having thus described my invention, what I claim as new, and desire to secure by Letters Patent, is—

As a new article of manufacture, an opera-glass the barrels or body portion of which are constructed of single thick metallic tubes, the external and exposed portions of which are hand-chased to roughen and ornament the 85 same, substantially as set forth.

In testimony whereof I affix my signature in presence of two witnesses.

JOSEPH FREDERICK FRADLEY.

Witnesses:

ALFRED JOHN GREGORY,
JEREMIAH JOHN EDWARDS.
